UNITED STATES PATENT OFFICE.

ROBERT E. NAUMBURG, OF WINCHESTER, MASSACHUSETTS, ASSIGNOR TO SACO-LOWELL SHOPS, OF LOWELL, MASSACHUSETTS, A CORPORATION OF MASSACHUSETTS.

TENSION DEVICE.

Application filed October 8, 1921. Serial No. 506,409.

To all whom it may concern:

Be it known that I, ROBERT E. NAUMBURG, a citizen of the United States, and a resident of Winchester, county of Middlesex, and 5 Commonwealth of Massachusetts, have invented certain new and useful Improvements in Tension Devices, of which the following is a specification.

This invention relates to a thread or yarn 10 tension device. I shall illustrate and describe the invention as applied to a spooling machine, although it is useful in many different kinds of machines which require tension devices, such as sewing, winding and 15 other textile machinery.

In the handling of thread or yarn in such machines, there are numerous difficulties which make a suitable tension device a matter of considerable importance. In a spooling machine, for example, the drag of the 20 yarn as it leaves the bobbin varies within wide limits, and it is important that there should be a tension device between the bobbin and the spool which will make the tension on 25 the thread as it is wound on the spool as uniform as possible throughout the operation, in order to obtain a firmly wound spool. Also as the body of yarn on the spool increases in diameter during the winding operation, the revolution of the spool being constant, the surface speed of the yarn increases, 30 causing a greater tension on the outer layers of yarn than on the inner layers. This variation in the surface speed of the yarn must 35 be compensated for by the tension device without undue strain on the yarn. Again, when the traverse mechanism of the spooling machine reaches the top or the bottom of its stroke, it changes its direction of movement 40 abruptly, causing a sudden strain on the yarn, which with the ordinary tension devices now in use is the cause of frequent breakages. It is advisable that the tension device should be so organized that the normal 45 tension on the yarn can be easily varied according to the fineness of the yarn, and also that a series of tension devices can be adjusted uniformly by comparatively unskilled persons. Furthermore, all yarns have 50 uneven places which must pass through the tension device, and the tension device should permit the passage of such uneven places without undue strain on the yarn.

Among other advantages, my new im-

provement embodies means whereby both 55 changes in tension as the yarn leaves the bobbin and variations in surface speed of the yarn on the spool are quickly compensated for without undue strain on the yarn. Strains due to the abrupt changes in direction of movement of the traverse mechanism 60 are prevented, and uneven places in the yarn are permitted to pass through the tension device without strain on the yarn. Furthermore, my new tension device is so organized 65 that the tension on the thread can be easily varied, and a series of such tension devices can be easily adjusted uniformly by unskilled persons. Other advantages will appear as 70 the invention is described.

Fig. 1 is a side elevation, partly in section, of my device in place on a spooling machine. Fig. 2 is a plan view of the device. Fig. 3 is a front elevation of one form of my device. Fig. 4 shows the device of Fig. 3 with the 75 cup or disk tilted in a somewhat exaggerated manner to illustrate the action of the device under certain conditions. Fig. 5 is a front elevation of the preferred form of my device with certain parts in section. Fig. 6 80 shows the device of Fig. 5 with the cup or disk tilted in somewhat exaggerated form to show the action of the device under certain conditions. Fig. 7 is a sectional view of a preferred form of cup.

Referring to Figs. 1, 2, 5 and 6, attached to the usual guide rail 1 by clamp 2 is the supporting member 3. A pin 4 is inserted in the supporting member 3 and held in place by a set screw 5. A cylindrical cap 6 is supported on the pin and threaded thereto as shown at 7. Mounted on the pin is a disk or cup 8, preferably concavo-convex in form as shown in Fig. 7, and with its convex surface normally resting on the supporting 85 member. Resting on the concave face of this disk is the spiral compression spring 9, shown as tapered at 10. On the top of the spring is the disk 11, and resting on said disk 11 and mounted on the pin are any 90 desired number of removable weights or washers 12, 12. The spring 9 as shown is of special shape, being tapered at 10 so that at this point it is wound closely around the pin, thereby keeping its axis in line with the 95 center of the pin. Below point 10 the spring increases in diameter until it is substantially 100 the same in diameter as the inside of the 105

lower disk. Above point 10 the spring is expanded somewhat to make a bearing and friction surface against the under side of disk 11. This cup 11 may be omitted entirely in this form of my invention, permitting the weights 12, 12 to rest directly on the spring 9.

The disk 8 is made of thin, light metal and should have a loose fit on the pin and 10 have no barrel or collar, so that it may be easily and freely tilted sidewise. As shown it has a protruding bearing surface 13 and is recessed at the center at 14.

The yarn 15 is drawn from bobbin 16 over 15 the supporting member at 17 (see Fig. 2), under the disk 8, and thence over the guide rail 1, through the slab-catcher or thread guide 18 to the spool 19, in the ordinary manner, as shown in Fig. 1. If a thick place, 20 a bunch or a slab in the yarn passes under the disk, the disk will be tilted and the support will be shifted as shown in Fig. 6. The spring is compressed sideways as shown 25 in Fig. 6, the pressure on the spring acting at an angle and not directly along the axis 30 of the pin, with the result that the thick place in the yarn is permitted to pass through the tension device without interruption or strain on the yarn by this slight 35 tilting of disk 8, and the slight sideways compression of the spring. The desired result is effected, therefore, without lifting the whole disk and without lifting the weights and overcoming the inertia of the 40 weights, which would ordinarily involve a strain on the yarn.

The fact that the whole disk 8 need not 45 be lifted and that the inertia of the weights need not be overcome when an uneven place or an uneven strain comes on the yarn, permits a quick and delicate response to changes in the yarn. Similarly, when the traverse mechanism changes its direction of motion, and whenever there is any change in tension 50 on the yarn there is a quick and delicate response and the spring acts as a shock absorber in avoiding sudden changes in pressure of the weights.

My invention retains the advantages of 55 a spinning tension device. The yarn by its frictional contact with the disk 8 causes the cup to spin rapidly, the rotary motion being transmitted by means of friction to the spring 9 and thence to the disk 11, if used, and to the weights 12, 12. This spinning of the tension device assists in evening the tension of the yarn and is of importance in cleaning the yarn.

Another advantage in my invention appears in the threading operation. If there 60 were no such tilting and yielding members as the disk 8 and the spring 9, it would be necessary for the thread or yarn to actually lift the disk or the disk and the weights 12, 12 in order to slide into place. In my device

there is little resistance to the thread slipping under the disk 8, as it is easily tilted as already described and shown in Fig. 6.

The cap 6 serves a useful purpose in shielding and protecting the whole device. 70 It also presents the proper surface to guide the yarn or thread into place between the supporting member and the disk 8, when, as is usual, the thread is simply passed by the operator over the supporting member 75 between arms 23 and 24, and around the cap and allowed to find its place, as shown in Fig. 2. In other words, the cap makes the device more surely and positively self-threading. 80

Another form of my device is shown in Figs. 3 and 4. In this modified form of my device, as the spring 9' is not tapered it is necessary that it should support the upper cup or disk 11' which has a hub or barrel 85 20' to keep it from tilting sideways. Also the pin 4' is U-shaped and the weights 12' 12' have cuts 21' by which they can be removed from the pin 4' at notch 22'. 90

It will be noted that in both constructions shown the force exerted on the disks 8 and 8' depends substantially upon the number of weights on the pin and that the compression on the spring is adjustable, not by a lock nut or other device but simply by the number of weights. The number of weights can be readily varied and a series of tension devices can be made substantially uniform in operation by placing on each the same 95 number of uniform weights. 100

It will be appreciated that the embodiments of my invention here shown and described may be modified in many particulars without departing from the spirit or scope of this invention. 105

Having described my invention, what I desire to claim as new is:—

1. In a tension device, a support, a pin carried thereon, a disk mounted on said pin and resting on said support, a compression spring resting on said disk and mounted on said pin, said spring being tapered at a point above its base so as to fit the pin closely at said tapered point, and a weight mounted on said pin and resting on said spring. 110

2. In a tension device, a support, a pin carried thereon, a disk resting on said support and loosely mounted on said pin, a compression spring mounted on said pin and resting on said disk, a weight removably mounted on said pin and resting on said spring, and a cap removably mounted on said pin. 120

3. In a tension device, a support, a pin carried thereon, a disk resting on said support and loosely mounted on said pin, a compression spring mounted on said pin and resting on said disk, a weight removably mounted on said pin and resting on said 125 130

spring, and a cylindrical cap removably mounted on said pin.

4. In a tension device, a support, a pin carried thereon, a concavo-convex cup with 5 its convex face resting on said support, a compression spring mounted on said pin and with its base resting on the concave surface of said cup, a plurality of removable weights mounted on said pin and resting on said

spring, and a cylindrical cap covering said 10 spring and weights.

In witness whereof I have signed my name to the foregoing specification in the presence of two witnesses.

ROBERT E. NAUMBURG.
